INTERNAL-COMBUSTION ENGINE PISTON

Filed Dec. 30, 1943

FIG. 1

FIG. 2

FIG. 3

INVENTOR.
Landon B. Boyd
BY
Charles W. Dake
Attorney

My present invention relates to improvements in pistons, and particularly to pistons for internal combustion engines having a cylinder block structure and a cylinder cover; and the objects of improvement are: first, to provide an internal combustion engine piston that will cause improved combustion of the fuel charge in fuel spaces of the engine; second, to provide an internal combustion engine piston having a thin layer of substantially pure copper forming a heat radiant extending throughout its head for reflecting heat of combustion back into the combustion chamber; third, to provide an internal combustion engine piston having a member of copper extending throughout its head portion that does not act as a heat transfer member; fourth, to provide an internal combustion engine piston having less heat transfer to the wall of the cylinder in which the piston reciprocates than either pistons composed of non-ferrous metal or such other pistons having copper or other non-ferrous metal at their heads; fifth, to provide an internal combustion engine piston that can operate on its reciprocative excursions with less clearance between its periphery and the cylinder wall than the internal combustion engine pistons presently employed; sixth, to provide an internal combustion engine piston that will remain substantially free from carbon accumulation under its deck and on the top of the piston; seventh, to provide an internal combustion engine piston of which the pressure sealing rings will not become carbon bound; eighth, to provide an internal combustion engine piston whereby the horse power output of the engine will be greater than that of internal combustion engines of the same horse power rating and using the same quantity and quality fuel; ninth, to provide an internal combustion engine piston that will cause a minimum of fuel consumption for a given horse power developed by the engine; tenth, to provide an internal combustion engine piston that will cause a minimum consumption of lubricating oil; eleventh, to provide an internal combustion engine piston that will be more efficient than such pistons at present employed.

I attain these named objects and such other objects as appear from a perusal of the following description and the structure illustrated in the accompanying drawing, in which:

Figure 1 is a vertical sectional view of an internal combustion engine cylinder block having a cylinder cover extending over its top and a cylinder sleeve having a piston of my improved structure therein.

Figure 2 is an elevation view of my piston in part section.

Figure 3 is an enlarged cross-sectional view of a portion of an internal combustion engine piston illustrating the application of copper or other metals by other than my preferred method.

Throughout the three views of the drawing, similar numerals refer to similar parts and portions of my piston, as mounted in an internal combustion engine, and referring to the drawing:

Numeral 1 refers to my present internal combustion engine piston, comprising a skirt portion 2 with inwardly extending wrist pin bosses 3, each having a bore 4 for receiving the wrist pin 5, to which is swingably connected rod 6 connected to the crank pin of the engine's crank shaft, and whereby the crank shaft is turned by the piston on its power excursion and the piston is moved longitudinally by power stored in the crank shaft 20 and associated members on its compression excursion.

The skirt portion 2 has near its lower end, an annular ring slot 7, having loosely mounted therein outwardly springable oil film regulating ring 25 8, and near its upper end a thickened portion 9 having a plurality of annular slots 10, each having therein an outwardly springable pressure sealing ring 10' and outwardly extending annular flange 11 of slightly less diameter than the 30 skirt portion and the lands separating the pressure sealing ring slots.

At the top of the thickened portion 9 and forming a portion of the outwardly extending annular flange 11 is the piston head or deck 12, having secured to its side nearest to the combustion of the fuel charge a thin ferrous metal plate 12' having a higher resistance to heat transfer than the metal of the said deck 12, secured to the deck 12 preferably by brazing with a high temperature 40 melting point solder, and has at its side opposite the side from the said head deck a smooth heat reflecting layer 13 having high heat reflecting characteristics such as copper. Both the plate 12' and heat reflecting layer 13 are shown extending throughout the top surface of the head deck 12 and with the heat reflecting layer extending beyond the periphery of the annular flange 11 with a thin beveled edge 13' lightly engaging the wall of the cylinder bore in which the 45 piston is caused to reciprocate.

Numeral 14 refers to a cylinder block or frame of an internal combustion engine provided with a cylinder sleeve 15 having outwardly extending annular flange 16 at its top resting on annular 55 ledge 17 of the cylinder block or frame, having

4 Claims. (Cl. 123—193)

2

Figure 2 is an elevation view of my piston in part section.

Figure 3 is an enlarged cross-sectional view of a portion of an internal combustion engine piston illustrating the application of copper or other metals by other than my preferred method.

Throughout the three views of the drawing, similar numerals refer to similar parts and portions of my piston, as mounted in an internal combustion engine, and referring to the drawing:

Numeral 1 refers to my present internal combustion engine piston, comprising a skirt portion 2 with inwardly extending wrist pin bosses 3, each having a bore 4 for receiving the wrist pin 5, to which is swingably connected rod 6 connected to the crank pin of the engine's crank shaft, and whereby the crank shaft is turned by the piston on its power excursion and the piston is moved longitudinally by power stored in the crank shaft 20 and associated members on its compression excursion.

The skirt portion 2 has near its lower end, an annular ring slot 7, having loosely mounted therein outwardly springable oil film regulating ring 25 8, and near its upper end a thickened portion 9 having a plurality of annular slots 10, each having therein an outwardly springable pressure sealing ring 10' and outwardly extending annular flange 11 of slightly less diameter than the 30 skirt portion and the lands separating the pressure sealing ring slots.

At the top of the thickened portion 9 and forming a portion of the outwardly extending annular flange 11 is the piston head or deck 12, having secured to its side nearest to the combustion of the fuel charge a thin ferrous metal plate 12' having a higher resistance to heat transfer than the metal of the said deck 12, secured to the deck 12 preferably by brazing with a high temperature 40 melting point solder, and has at its side opposite the side from the said head deck a smooth heat reflecting layer 13 having high heat reflecting characteristics such as copper. Both the plate 12' and heat reflecting layer 13 are shown extending throughout the top surface of the head deck 12 and with the heat reflecting layer extending beyond the periphery of the annular flange 11 with a thin beveled edge 13' lightly engaging the wall of the cylinder bore in which the 45 piston is caused to reciprocate.

Numeral 14 refers to a cylinder block or frame of an internal combustion engine provided with a cylinder sleeve 15 having outwardly extending annular flange 16 at its top resting on annular 55 ledge 17 of the cylinder block or frame, having

cylinder cover 18 secured to its top surface with a suitable high pressure heat resisting packing interposed between the cylinder block and cover.

Numerals 19 refers to the combustion chamber of the engine which should be of suitable form for the engine in which the piston is to be used, as different designs of engine require differently formed combustion chambers. Numeral 20 refers to the fuel intake valve operated by the valve stem 21 for admitting gaseous fuel to the combustion chamber 19 from fuel intake passage 22; numeral 23 designates the ignition spark plug and 24 the chamber containing the cooling fluid of the cylinder block or frame.

Referring to Figure 3 therein is shown a method of securing copper directly to the top of the piston's head by the metal being melted into a recess extending over the deck of the piston, and into annular grooves 26 machined into the said deck. This method forms no part of the subject of the present application, the view merely shows a method whereby copper or other metal having a lower melting temperature than ferrous metal can be applied to the head of a piston.

Applicant is aware that prior to his present invention copper of considerable thickness has been attached to the head portion of internal combustion engine pistons for the express purpose of uniformly transferring heat caused by combustion in the combustion spaces above the piston to the head of the piston to be dissipated by air circulated within the piston against the under side of the head, and also conveyed by the head to the surrounding skirt portion and therefrom to the cylinder wall, which of most internal combustion engines is surrounded by a cooling fluid circulated through cooling fluid chambers and air cooled radiators, all making it necessary to provide sufficient metal throughout the piston structure to carry the heat of combustion to the cylinder wall and resulting in a heavier piston than is necessary in my piston structure, where the heat of combustion is reflected back into the combustion spaces with only a minor portion of the heat reaching the cylinder wall.

In my piston structure, the copper layer, which is substantially pure acts as a heat radiant without sufficient thickness to absorb any appreciable quantity of heat and has only a knife edge contacting the cylinder wall, and therefor can not transfer heat to the cylinder wall in any appreciable amount; also, the copper layer 13 or other satisfactory nonferrous metal that might be employed having similar heat characteristics, is being secured to the ferrous metal plate 12' having a higher resistance to heat transfer than the metal of said deck 12 and which in turn is secured to the head deck of the pistons, forms a resistance to combustion heat transfer from the copper to the head deck of the piston and to the oil and atmosphere circulating within the piston; all of which contribute to producing higher operating efficiency of the engine in whole, as the thin layer of copper being smooth at its combustion exposed surface acts as a radiant to reflect or deflect and throw back into the combustion spaces of the engine heat to cause uniform heating of the succeeding gaseous fuel charges drawn into the combustion spaces of the engine and thereby more nearly perfect and uniform combustion of the

fuel is obtained; further, the thinness of the copper metal layer 13 approximately one sixty-fourth of an inch coupled with its joinder zone between it and the ferrous plate to which it is attached and the joint of said plate with the piston head deck, form a dam in part that resists heat transfer of combustion to the piston and particularly to the under side of the head deck, and thereby prevents accumulation of carbon within the piston; as where the lubricating oil is splashed against the under side of the head deck of a piston when heated, as it is in internal combustion engines having assisted heat transfer by a heat transfer means, form a deposit of carbon throughout most of the interior of the piston, and also in the pressure sealing ring grooves, thereby preventing free action of the rings. This formation of carbon in the piston contributes to excessive oil consumption and the prevention of pressure sealing ring free action contributes to high fuel consumption.

In my internal combustion engine piston there is the layer of substantially pure copper metal of approximately one-sixty-fourth inch thickness, which acts as a radiant to divert or throw back into the combustion spaces of the engine, heat caused by combustion, and to the means of attaching the copper to the ferrous metal plate, and the ferrous metal plate to the head deck, together with the ferrous metal plate, dampens heat transfer to the piston skirt and cylinder wall with its dissipation by a cooling medium.

Having described my present invention relating to internal combustion engine pistons, I claim:

1. An internal combustion engine piston having a copper metal layer forming a heat reflector at its head, and fastened thereon by a ferrous metal plate secured to the head deck of the piston and having a lesser heat conduction factor than the heat conduction factor of the copper for reflecting back into the combustion spaces heat caused by combustion of fuel in said combustion spaces.

2. In an internal combustion engine piston having a skirt with a head deck associated therewith, machined at its top side exterior of the piston, a ferrous metal plate joined to the machined side of the head deck of the piston, and having at its opposite side from the head deck a heat radiant surface for reflecting heat of combustion back into the combustion spaces of the engine.

3. In an internal combustion engine piston having a skirt and a head deck the head deck having with a machined side external of the piston, a steel plate having a copper metal layer not exceeding one sixty-fourth inch thick joined to one of its flat sides, with the steel plate fused to the machined side of the head deck.

4. In an internal combustion engine piston, the combination of a hollow piston body having a head deck closing one of its ends with a ferrous metal plate having a fused joinder with the head deck exterior of the piston, and having a nonferrous metal layer integral with the ferrous metal plate at the opposite side thereof from the head deck.
